US0D1002006S

(12) **United States Design Patent** (10) **Patent No.:** **US D1,002,006 S**
Godinez et al. (45) **Date of Patent:** **** Oct. 17, 2023**

(54) **SECUREMENT DEVICE ASSEMBLY
COMPONENT**

(71) Applicant: **Medline Industries, LP**, Northfield, IL (US)

(72) Inventors: **Saul Godinez**, Chicago, IL (US); **Michael Turturro**, Arlington Heights, IL (US); **Darin Decker**, Chicago, IL (US); **Karen Daunov**, Chicago, IL (US); **Greg Corey**, Evanston, IL (US); **Derek Roberts**, Boston, MA (US)

(73) Assignee: **Medline Industries, LP**, Northfield, IL (US)

(**) Term: **15 Years**

(21) Appl. No.: **29/739,867**

(22) Filed: **Jun. 30, 2020**

Related U.S. Application Data

(62) Division of application No. 29/606,291, filed on Jun. 2, 2017, now Pat. No. Des. 890,924.

CLAIM

The ornamental design for a securement device assembly component, as shown and described.

DESCRIPTION

FIG. 1 is a top perspective view of a securement device assembly component showing our new design;

FIG. 2 is a bottom perspective view thereof;

FIG. 3 is a top plan view thereof;

FIG. 4 is a right side elevation view thereof, the left side elevation view being a mirror image thereof;

FIG. 5 is a front elevation view thereof;

FIG. 6 is a rear elevation view thereof; and,

FIG. 7 is a bottom plan view thereof.

The broken lines depict portions of the component that form no part of the claimed design.

1 Claim, 7 Drawing Sheets
